UNITED STATES PATENT OFFICE.

HARRY SCHWERIN, OF BROOKLYN, NEW YORK.

DESIGN FOR FOOTWEAR.

61,383.

Specification for Design. Patented Aug. 15, 1922.

Application filed July 23, 1921. Serial No. 487,197. Term of patent 3½ years.

To all whom it may concern:

Be it known that I, HARRY SCHWERIN, a citizen of the United States, residing at borough of Brooklyn, in the county of Kings and State of New York, have invented a new, original, and ornamental Design for Footwear, of which the following is a specification, reference being had to the accompanying drawing, forming part thereof.

Fig. 1, is an elevation of a boot, embodying my new design, and

Fig. 2, is a plan view of the cuff portion of the shoe, flattened to show the whole design.

I claim:

The ornamental design for footwear as shown.

HARRY SCHWERIN.
